UNITED STATES PATENT OFFICE.

WILLIAM R. UHLEMANN, OF CHICAGO, ILLINOIS.

LENS-MOUNT.

1,109,189.

Specification of Letters Patent. Patented Sept. 1, 1914.

Application filed August 13, 1913. Serial No. 784,549.

To all whom it may concern:

Be it known that I, WILLIAM R. UHLEMANN, a citizen of the United States of America, and a resident of Chicago, in the county of Cook, State of Illinois, have invented certain new and useful Improvements in Lens-Mounts, of which the following is a specification.

This invention relates to that type of lens mounts in which the clips are secured to the lenses without the use of clamping screws, and without any material encroachment upon the field of vision of the lenses. And the present improvement has for its object to provide a simple and efficient structural formation and combination of parts whereby a strong and effective attachment is effected in a convenient and economical manner, all as will hereinafter more fully appear.

In the accompanying drawings:—Figure 1, is a detail perspective view, illustrating the general arrangement of parts in the present invention as applied to an eyeglass. Fig. 2, is a sectional view of the lens mount, on line $x-x$, Fig. 3, showing the same in place upon a lens. Fig. 3, is a rear elevation of the mount. Fig. 4, is a transverse section of the mount, on line $x'-x'$, Fig. 2. Fig. 5, is a sectional view of a modified form of mount.

Similar reference numerals indicate like parts in the several views.

Referring to the drawings, 1 represents a portion of an eyeglass lens, which in the present construction is formed with a pair of radial notches 2 in its perimeter, said notches being disposed equidistant from a line representing the major diameter of the lens, as shown.

3 is the box clip of the present construction, formed of gold or other suitable metal or material, and comprising a curved back portion or web 4, a pair of side flanges or webs 5, and a pair of transverse engaging tongues or webs 6. In the preferred form of the present invention illustrated in Figs. 2, 3 and 4, the above described webs 4, 5 and 6, are shown as an integral or one piece formation, it is however within the province of this part of the present invention to make the transverse engaging tongues or webs 6, separate from the other webs, and preferably in the connected form shown in Fig. 5, and subsequently brazed or riveted to the back portion or web 4, of the box clip.

The curved back portion or web 4, will preferably have a curve of a lesser radius than the radius of the end lens 1, in order to provide a semi-lunar cavity at the edge 60 of the lens for holding a body of the cementing composition employed in securing the clip in place, and thereby attain a very effective union of the parts, and so that the bearing between the parts will only be near 65 the respective ends of the web 4, as illustrated in Fig. 2 to confine the cementing composition in place and materially aid in attaining a strong and durable attachment 70 of the eyeglass parts. The side webs 5 will 70 preferably have their greatest width in proximity to the engaging tongues or webs 6, with a comparatively narrow central portion 7 separating said wider portions, and permitting of a limited flexure or bending 75 of the clip, when required in the initial fitting of the clip to the lens.

In the preferred form of the present invention shown in the drawings, the attachment of the transverse engaging tongues or webs 6, is wholly with the back web 4, leaving the side edges of said tongues or webs 6 free from any connection with the side webs 5. Such construction permits of a free 80 swinging apart of the free ends of said 85 tongues or webs so that they may readily pass over the wider outer portion of the segment of the lens formed by the radial notches 2, in the operation of connecting the 90 clip to the lens.

In actual use, a suitable cement will be employed between the interior of the clip and the exterior of the lens, to aid the mechanical construction above described in effecting a strong and substantial connection 95 between the parts.

8 is the usual attaching box, in which an end of the eyeglass bridge 9 is secured in any usual manner, and said box 8 may be disposed at the rear of the clip 3, as shown in 100 Fig. 1, or in any other usual position on the clip which the judgment of the optician may indicate.

Having thus fully described my said invention, what I claim as new and desire to 105 secure by Letters Patent, is:—

1. A lens mount, comprising a box clip formed with a curved and continuous back web, a pair of side webs and a pair of transverse attaching webs, providing in connection with a lens a closed cavity adapted to 110 retain a cementing body, said attaching webs

being adapted to be sprung into radial notches in the perimeter of a lens.

2. A lens mount, comprising a box clip formed with a curved and continuous back web, a pair of side webs and a pair of transverse attaching webs, providing in connection with a lens a closed cavity adapted to retain a cementing body, said attaching webs being adapted to be sprung into radial notches in the perimeter of a lens, each side web comprising a pair of widened portions connected together by a narrow central portion adapting the clip to be symmetrically bent to fit varying curvatures of the perimeter of the lens.

3. A lens mount, comprising a box clip formed with a curved and continuous back web, a pair of side webs and a pair of transverse attaching webs connected solely to the back web and free from connection with the side webs providing in connection with a lens a closed cavity adapted to retain a cementing body, the said attaching webs being adapted to be sprung into radial notches in the perimeter of a lens, each side web comprising a pair of widened portions connected together by a narrow central portion adapting the clip to be symmetrically bent to fit varying curvatures of the perimeter of the lens.

4. A lens mount, comprising a box clip formed with a curved and continuous back web, the radius of which is smaller than the perimeter of the lens to which attachment is to be made, a pair of side webs, and a pair of transverse attaching webs, said attaching webs being adapted to be sprung into radial notches in the perimeter of a lens, the said back and side webs providing in connection with a lens a closed cavity adapted to retain a cementing body.

5. A lens mount, comprising a box clip formed with a curved and continuous back web, the radius of which is smaller than the

perimeter of the lens to which attachment is to be made, a pair of side webs, and a pair of transverse attaching webs connected solely to the back web and free from connection with the side webs, the said attaching webs being adapted to be sprung into radial notches in the perimeter of a lens, the said back and side webs providing in connection with a lens a closed cavity adapted to retain a cementing body.

6. A lens mount, comprising a box clip formed with a curved and continuous back web, the radius of which is smaller than the perimeter of the lens to which attachment is to be made, a pair of side webs, and a pair of transverse attaching webs, said attaching webs being adapted to be sprung into radial notches in the perimeter of a lens, the said back and side webs providing in connection with a lens a closed cavity adapted to retain a cementing body, each side web comprising a pair of widened portions connected together by a narrow central portion.

7. A lens mount, comprising a box clip formed with a curved and continuous back web, the radius of which is smaller than the perimeter of the lens to which attachment is to be made, a pair of side webs, and a pair of transverse attaching webs connected solely to the back web and free from connection with the side webs, the said attaching webs being adapted to be sprung into radial notches in the perimeter of a lens, the said back and side webs providing in connection with a lens a closed cavity adapted to retain a cementing body, each side web comprising a pair of widened portions connected together by a narrow central portion.

Signed at Chicago, Illinois, this 9th day of August 1913.

WILLIAM R. UHLEMANN.
